UNITED STATES PATENT OFFICE

HARRY R. DECKER, OF HOUSTON, TEXAS, ASSIGNOR TO DECKER OIL TOOL COMPANY, OF HOUSTON, TEXAS, A CORPORATION OF TEXAS

ROTARY SLIP

Application filed December 18, 1923. Serial No. 681,836.

This invention relates to new and useful improvements in a rotary slip.

One object of the invention is to provide a slip of the character described specially designed for the purpose of holding pipe suspended from a rotary in a well bore.

Another object of the invention is to provide a sectional slip which will readily conform to the shape of, and engage with, the pipe to be held.

A further feature of the invention resides in the provision of a pipe engaging slip having internal teeth so formed that they will readily bite into and securely hold the pipe in the rotary and the outer faces or sides of whose jaws will have small frictional contact with the rotary, in which the slip is seated, so that the slip can be easily unseated from the rotary.

20 A still further feature of the invention resides in the provision of a rotary slip which, when engaged with the pipe, will hold the same against turning in case it is desired to unscrew or screw together joints of the pipe above the rotary, thus eliminating the use of back up tongs.

The slip herein described is very flexible, of simple and light construction, and may be cheaply and easily manufactured, and easily 30 and conveniently handled in use.

With the above and other objects in view, the invention has particular relation to certain novel features of construction, operation and arrangement of parts, an example of 35 which is given in this specification and illustrated in the accompanying drawings, wherein:

Figure 1 shows a plan view of one form of the slip, partly in section.

40 Figure 2 shows a vertical sectional view thereof.

Figure 3 shows a side elevation of one section thereof.

45 Figure 4 shows a vertical sectional view thereof, as slightly modified.

Figure 5 shows a plan view of another type of the slip, partly in section.

50 Figure 6 shows a vertical sectional view thereof.

Figure 7 shows a side view of one section thereof; and,

Figure 8 shows a vertical sectional view of still another form of the slip.

Referring now more particularly to the drawings, wherein like numerals of reference designate similar parts in each of the figures, the numerals 1, 1 designate the slip sections, as a whole. Each section is composed of a plurality of pipe engaging jaws 2, spaced 55 apart and secured together, as hereinafter stated. As shown in Figures 1, 2 and 3 the jaws 2, of each section are flexibly secured to an arcuate anchor bar 3 by means of stud bolts 4 which are fitted loosely through said bar and threaded into the tapped holes 5 in the upper ends of the respective jaws 2. The upper ends of these bolts are suitably headed 60 to prevent the detachment of the jaws. In order to prevent the jaws from turning on a vertical axis the upper end of each jaw has a pin 7 which projects loosely up into a socket 6 provided in the under side of the bar 3. If desired, the lower end of each jaw may be provided with a transverse notch 9, and a section 65 of wire rope, as 8, may be fitted into the notches of the jaws of each slip section and secured therein by means of set bolts, as 10, which are forced through the rope, between the strands thereof, and screwed into a tapped 70 hole in the lower end of the corresponding jaw, as shown in Figures 1, 2 and 4. This prevents the lower ends of the jaws from swinging 75 out of proper alignment.

In Figure 4 the anchor bar 3' is provided, 85 around its under side, with a dovetailed groove 11, and the upper end of each jaw has a dovetailed projection 12 adapted to fit into said groove, and a set bolt 13 is passed through said bar and threaded into the upper end of 90 each jaw to hold the jaws against lateral movement around the groove 11. In other respects, the form shown in Figure 4 is similar to that shown in Figures 1, 2 and 3.

In the form shown in Figures 5, 6 and 7 the 95 bar 14 is somewhat narrower than the bars 3 and 3', of Figures 1 to 4, and the upper end of the jaws 2 are shouldered in to form an inside upward extension 15 which rests against the inner side of the bar 14, and prevents the 100

jaws from turning around on a vertical axis. The lower ends of the jaws 2, in this form have vertical notches 22, and in these notches, of each section, there are fitted loosely arcuate stay bars 23 which are secured in place by the pins 24 which are threaded through the jaws and whose inner blank end projects through aligned holes in said stay bar. This arrangement holds the lower ends of the jaws in arcuate alignment. In other respects the form shown in Figures 5, 6 and 7 is similar to the form shown in Figures 1, 2 and 3.

In Figure 8 there is shown another modification wherein the upper ends of the jaws are provided with notches 17, and the anchor bar 14' has a depending arcuate rib 16 which is fitted into said notches loosely and the jaws are secured, loosely, to said rib by the transverse pins 18 which pass through the jaws and also pass loosely through said rib. The lower ends of the jaws, in this form, are shouldered in, as at 19, and a surrounding arcuate stay bar 20 is fitted into the shouldered in portions of the jaws of each section, and secured to the jaws by pins 21 which are screwed through the stay bar and whose inner ends are blank, and project through aligned holes in the lower ends of the jaws. In other respects, the form shown in Figure 8 is similar to the form shown in Figures 1, 2 and 3.

Each section of the slip is provided with a U-shaped handle 25 whose ends are outwardly turned and fitted through bearings 26 formed in the upwardly extended ends of some of the stud bolts, 4.

In all the forms, the inner edge of each jaw is transversely toothed as at 27. It is to be noted that these teeth are straight so that the central part of the teeth will first contact with and bite into the pipe, as illustrated in Figures 1 and 5. The teeth will thus more readily take hold of the pipe, and furthermore, when the pipe is thus engaged, all the way around the slip will act as a wrench to hold the pipe against turning in the slip when it is desired to screw a joint onto or unscrew it from the upper end of the pipe. Likewise, the outer edge of each jaw is straight, that is, it is parallel to the teeth, or, in other words, is parallel to a line tangential to the pipe, so that only the outer corners of the jaws will contact with the wall of the rotary spider, thus reducing the frictional surface, to the end that the great weight of the load of pipe carried by the slip will not seat the slip in said spider so tightly that the slip will not readily release itself from the spider when it is desired to remove the same.

It is to be noted that each jaw is comparatively thin transversely with respect to its radial diameter, and the jaws are spaced a considerable distance apart, thus providing a very light, yet strong, construction, and as the parts are all loosely connected together,

a very flexible slip is thus provided, which will readily conform to the shape of the pipe, and engage with it all the way around. It is further to be noted that the outer side of each jaw tapers downwardly, relative to the inner toothed face thereof, so as to form a perfect seat with the downwardly and inwardly tapering spider of the rotary.

What I claim is:

1. A pipe holding slip formed of sections, each section including a plurality of jaws, each jaw being relatively thin with respect to its radial and longitudinal dimensions, means connecting said jaws loosely together and at the same time holding them in spaced relation, said means including wire rope at the lower ends of the jaws and means for moving each section independent of the other section.

2. A pipe holding slip formed of sections, each section including a plurality of jaws, each jaw being relatively thin with respect to its radial dimension, means connecting said jaws loosely together and at the same time holding them in spaced relation, said means including an arcuate bar at the upper ends of said jaws, the abutting parts of each jaw and said bar being provided one with a recess and the other with a projection fitting into said recess and a pin fitted through said projection and also being fitted into a bearing in the adjacent connected part and connecting said parts together.

3. A pipe holding slip formed of sections, each section including a plurality of jaws, each jaw being relatively thin with respect to its radial dimension, means connecting the jaws of a section loosely together and at the same time holding them in spaced relation, said means including an arcuate bar at the upper ends of said jaws, the abutting parts of each jaw of a section and the corresponding bar being provided one with a projection and the other with a recess to receive the projection and a pin fitted through said abutting parts of the bar and of each jaw and connecting said abutting parts together.

In testimony whereof I have signed my name to this specification.

HARRY R. DECKER.
